UNITED STATES PATENT OFFICE.

HAROLD W. BUCK, OF NEW YORK, N. Y., ASSIGNOR TO GENERAL ELECTRIC COMPANY, A CORPORATION OF NEW YORK.

LIGHTNING-ARRESTER RESISTANCE.

No. 895,956.

Specification of Letters Patent. Patented Aug. 11, 1908.

Application filed January 25, 1907. Serial No. 354,092.

To all whom it may concern:

Be it known that I, HAROLD W. BUCK, a citizen of the United States, residing at New York, county of New York, State of New York, have invented certain new and useful Improvements in Lightning-Arrester Resistances, of which the following is a specification.

Several types of lightning arresters now on the market include a resistance connected in series with spark gaps. These resistances are in some cases made of graphite or carborundum pressed into the form of a pencil and then fired.

15 My present invention comprises a new type of resistance possessing many advantages and suitable for use in the place of the graphite and carborundum pencils above mentioned; or in fact, suitable for use in connection with any lightning arrester subject to large currents. My improved form of resistance may be subjected to sudden heating without the fear that it will crack or disintegrate or change materially in resistance.

My invention comprises a woven hose or tube of fibrous fire proof insulating material filled with loose granules of powdered resistance material. A hose of this kind may be 30 woven of any length or diameter, then filled with the resistance powder or mixture, and arranged in any convenient way as a lightning arrester resistance. One way of utilizing such a resistance is shown in the diagrammatic drawing accompanying this specification.

Figure 1 is a sectional elevation of a lightning arrester connected with one conductor of a transmission line; and Fig. 2 is a detail view of the flexible resistance.

The line conductor 1 is supported on standards or poles 2 in ordinary manner and is connected with a plurality of spark gaps 3, 4 and 5 mounted on the cross bar 6 connecting the standards 2. These spark gaps may be of the horn type or of other standard form and serve to insulate the line conductor from ground when the line is at normal potential. Spark gap 5, the last of the se-

ries, is connected directly to ground through 50 a resistance 7 of the type hereinafter described more in detail.

The series resistance comprises an outer tube or envelop 8 of non-conductive material, and a loose filling 9 of resistance material. I may make the envelop of fire proof material such as fibrous asbestos, and the filling may be powdered carborundum, kryptol, lamp black, graphite, or any one of the above substances mixed with sand, cement, or other non-conducting refractory materials to increase the resistance of the powder. The length and cross-section of the hose will depend somewhat on the voltage of the line to be protected, and on other 60 conditions of each particular installation. The hose is more or less flexible and can be hung directly from the spark gap support to ground as shown in the drawing. It is heat proof and cannot be cracked, even though 70 the current conducted to ground may be momentarily very high.

What I claim as new, and desire to secure by Letters Patent of the United States, is,—

1. A lightning arrester resistance consisting 75 of a flexible heat proof envelop containing granular resistance material.

2. A lightning arrester resistance consisting of a woven heat proof tube containing granular resistance material.

3. A flexible lightning arrester resistance, comprising a woven tube of fibrous fire proof insulating material filled with loose granules of powdered resistance material.

4. A flexible resistance unit for lightning 85 arresters, consisting of a woven envelop of fibrous asbestos with a filling of granular resistance material.

5. A resistance unit for lightning arresters, consisting of a woven heat proof tube of insulating material, filled with granular resistance material.

In witness whereof, I have hereunto set my hand this 22nd day of January, 1907.

HAROLD W. BUCK.
